CLAIM

The ornamental design for a cleaning apparatus, as shown and described.

DESCRIPTION

FIG. 1 is a top perspective view of a cleaning apparatus showing my new design;

FIG. 2 is a bottom perspective view thereof;

FIG. 3 is a front elevational view thereof;

FIG. 4 is a rear elevational view thereof;

FIG. 5 is a top plan view thereof;

FIG. 6 is a bottom view thereof;

FIG. 7 is a right-side elevational view thereof;

FIG. 8 is a left-side elevational view thereof; and,

FIG. 9 is a perspective view of the present invention attached to a children's ride-on vehicle.

The broken lines showing portions of the cleaning apparatus form no part of the claimed design. The broken line showing of the children's ride-on vehicle in FIG. 9 represents environment and forms no part of the claimed design.

1 Claim, 9 Drawing Sheets
